UNITED STATES PATENT OFFICE.

CHARLES D. BATCHELOR, OF PILLSBURY, ASSIGNOR OF ONE-HALF TO
GEORGE N. BRESSLER, OF LONG PRAIRIE, MINNESOTA.

SNOW-PLOW.

SPECIFICATION forming part of Letters Patent No. 336,833, dated February 23, 1886.

Application filed September 18, 1884. Serial No. 143,378. (No model.)

To all whom it may concern:

Be it known that I, CHARLES D. BATCHELOR, a citizen of the United States of America, residing at Pillsbury, in the county of Todd and State of Minnesota, have invented certain new and useful Improvements in Snow-Plows; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention has reference to snow-plows; and it consists in the construction and combination of the parts hereinafter fully described and set forth.

In the accompanying drawings, forming 20 part of this specification, Figure 1 is a perspective view representing my improved truck. Fig. 2 is a side elevation, one of the supporting-wheels being removed; and Fig. 3 is a transverse section on the dotted line $x x$ 25 of Fig. 2.

The invention consists, primarily, in the main truck or carriage, and a supplemental plow device designed for attachment to the truck to operate in front thereof.

30 A A represent two parallel beams, which are provided at their front and rear with bearings a , in which bear the front and rear axles, B B, of the truck. Upon each projecting end of the said shafts B is suitably secured an ordinary car-wheel, C. The said beams A A are spanned by bars D, which are located as shown in the drawings, a platform, E, being mounted on the rear ends of the beams A A, adjacent to the rear bar D. A longitudinal 35 bolster, b, connects the front and rear bars D together. Each of the bars D is recessed at either side of the bolster b, to present a bearing for one end portion of a shaft, c, the rear end of which projects through an opening in 40 a vertical partition, d, mounted on the platform E. A lever, e, is connected to the rear projecting end of each shaft c, and is adapted to be engaged by a spring, f, secured near the upper edge of the partition d, so as to hold 45 said lever against a shoulder, g, projecting from the upper portion of the said partition.

A platform, F, is eccentrically mounted and secured on each shaft c, so that when said shaft and lever e occupy the position indicated in Fig. 1 the inner edges of the said plates F 55 will lie adjacent to and flush with the bolster b. By eccentrically mounting each platform F on its shaft c the preponderance of load will be outside of each shaft, thereby requiring but little leverage to tilt each platform. 60

A vertical standard, h, bears in the bolster b at the front portion thereof, and has hinged thereto two guide or deflecting plates, G G, each of which carries at its inner side, near its free end, a loop, i, designed for the passage of 65 a stake, H, the lower end of which is pointed to enter an opening therefor in the platform F beneath. A brace, I, spans the space between the free ends of the plates G G, and is perforated near each end, to pass over the upper portions of the said stakes H H and bear on the upper edges of the plates G G. 70

The plow proper consists of two side blocks, J J, which are inclined, as shown in Figs. 1 and 2, which are connected together at their 75 front by an axle, on the ends of which are keyed small car-wheels K. The side blocks, J, are notched on their under side, near the rear, to engage and rest upon the front axle of the truck. A platform, L, is secured in an 80 inclined position upon J, and has its side portions, M, turned up to form vertical side walls, as shown in Fig. 1. A vertical plate, N, is secured centrally on the plate L, at the rear thereof and parallel with the side walls. 85

The operation of the machine is as follows: When the machine moves forward, the snow passes up the inclined plate L between the side walls, M, and it is directed by the plate N off to each side of the truck, from whence 90 it is deflected by means of the guards G. Said guards may, upon the removal of the stakes and cross-bar I, be folded parallel with each other upon the bar b and the snow rest upon the plates F. When a sufficient load has accumulated, the levers e may be disengaged from the shoulders g, so as to partially turn the shafts c in their bearings, thereby tilting the plates F to the position indicated by the dotted lines, Fig. 3, and consequently dumping the snow to either side of the track. 95

A shoe, O, depends from the under side of

the plate L, so as to embrace the track, and not only serves to clean the tracks in advance of the wheels, but affords a support for the front portion of said plate.

5 I claim—

1. The combination, in a snow-plow, of a truck having the rear platform, E, and vertical partition *d*, parallel shafts *c*, extending longitudinally and having their rear ends projecting through the said partition, levers connected to said projecting ends, and platforms F, connected to said shafts, to be tilted by the oscillation of the same, substantially as set forth.

15 2. The combination, in a snow-plow, of a truck, a plow adapted to be operated in advance of said truck and provided with an inclined scoop, and plates J, secured at its rear portion and notched to engage the front axle 20 of the adjacent truck, substantially as set forth.

3. The combination, in a snow-plow, of a supporting carriage or truck and an inclined plate provided with side blocks, J, notched to rest on the forward axle of the supporting carriage, and having side plates, M, and central plate, N, substantially as set forth. 25

4. The combination, in a snow-plow, of a truck, parallel shafts *c c*, longitudinally mounted in suitable bearings, a platform, F, mounted 30 on each shaft between its center and inner edge, and devices for operating said shafts to cause them to tilt the platform, substantially as set forth.

In testimony whereof I affix my signature in 35 presence of two witnesses.

CHARLES D. BATCHELOR.

Witnesses:

GEO. E. LEE,
FRANK PHILLIPS.
